Patented Dec. 22, 1959

186,873

CORD REEL FOR A VACUUM CLEANER OR SIMILAR ARTICLE

Michael E. Belicka, Greenwich, Allen P. Cawl, New Canaan, Lurelle V. A. Guild, Noroton Heights, and Robert C. Lampe, Stamford, Conn., assignors to Electrolux Corporation, Old Greenwich, Conn., a corporation of Delaware

Application January 5, 1959, Serial No. 54,033

Term of patent 14 years

(Cl. D9—2)

Fig. 1

Fig. 2

Fig. 3

Fig. 4

Fig. 5

Fig. 6

Fig. 1 is a side elevational view of a cord reel for a vacuum cleaner embodying our new design with the portion of vacuum cleaner shown in dotted lines for illustration purposes only;

Fig. 2 is an end elevational view as seen from the right of Fig. 1;

Fig. 3 is an end elevational view as seen from the opposite side of Fig. 2;

Fig. 4 is a side elevational view of the opposite side of the cord reel from that shown in Fig. 1;

Fig. 5 is a top plan view of the cord reel; and

Fig. 6 is a bottom plan view thereof.

We claim:

The ornamental design of a cord reel for a vacuum cleaner or similar article, as shown and described.
